UNITED STATES PATENT OFFICE

OSCAR CARLSON, OF EAST PROVIDENCE, RHODE ISLAND, ASSIGNOR TO DOLAN & BULLOCK, OF PROVIDENCE, RHODE ISLAND, A FIRM COMPOSED OF ARTHUR F. DOLAN AND FRED A. BULLOCK, BOTH OF ATTLEBORO, MASSACHUSETTS, AND WILLIAM G. BENNETT, OF PROVIDENCE, RHODE ISLAND

COLLAR HOLDER

Application filed February 8, 1930. Serial No. 426,957.

This invention relates to a collar holder; and has for its object to provide a collar holder which will have a resilient jaw and be easily operable consistent with the proper amount of holding power.

A further object of the invention is to provide a collar holder which is provided with jaws, one of which jaws will have spaced fabric engaging portions and the other of which will tend to force the fabric between these spaced portions to increase the gripping and holding power of the holder on the collar. A still further object of the invention is the offsetting of one of the bars which make up the jaws to control and insure a more resilient action between them.

With these and other objects in view, the invention consists of certain novel features of construction, as will be more fully described, and particularly pointed out in the appended claim.

In the accompanying drawings:

Fig. 1 is a side elevation of the improved collar holder.

Fig. 2 is a top plan view thereof.

Fig. 3 is a top plan view of the lower bar of the holder.

Fig. 4 is a side elevation of the top bar of the holder.

Fig. 5 is a section on the line 5-5 of Fig. 1.

Fig. 6 is a section on the line 6-6 of Fig. 2.

Fig. 7 is a side elevation of a modified form of holder, showing the bottom bar offset rather than the top bar.

Fig. 8 is a side elevation of a further modified form of holder.

Fig. 9 is a perspective view showing a still further modified form of holder member of sheet stock as distinguished from rolled wire used in the other constructions.

It is found desirable in forming collar holders to provide a pair of jaws which will have sufficient resiliency to permit a soft collar to be easily slipped between them but also will have sufficient holding power to tightly grip the collar and maintain the same in place; and in order to accomplish these results I have provided jaws one of

which is provided with spaced portions to permit the fabric to be pressed between them and cause the fabric to contact on these spaced jaws forming a two-point engagement; and in order to insure a proper resiliency I have offset one of the bars adjacent the point at which it is secured to the other bar thereby providing an easier movement of the jaws; and the following is a detailed description of the present embodiment of this invention illustrating the preferred means by which these advantageous results may be accomplished:

With reference to the drawings, 10 designates the lower bar which is formed of wire and folded at its opposite ends to provide loops 11, each loop has an opening 12 between the sides 13 and 14 thereof and is offset as at 15 to align the opening with the general extent of the bar 10 between the loop portions, the upper bar 16 having its ends rolled or curled as at 17, and offset at substantially its middle as at 18, to contact with the bar 10 about which offset portion is wrapped a suitable securing member 19 to hold the two bars in contact, the position of the parts being such as to cause the rolled end 17 of the upper bar to resiliently contact with the sides 13 and 14 of the looped portion 11 and be so aligned as to dispose its curled portion over the opening 12 of the loop which thus provides a set of jaws 20 and 21 with the loop 11 of one disposed in a plane substantially at right angles to the plane of the rolled end 17 of the opposite jaw 21. This arrangement provides spaced contact points 22 and 23 of each looped portion and tends to press the fabric of the soft collar into the space 12 while it is gripped on either side of this space at the contact points 22 and 23.

In the modification shown in Fig. 7, the lower bar 24 is offset as at 25, rather than the upper bar but is held in place by the securing member 19 similar to that previously described.

In the modification shown in Fig. 8, the jaws are formed of a single piece of wire folded upon itself similar to the jaws illustrated in Fig. 1, and these jaws 27 are connected together by a ring or open link 28 al-

lowing a loose or flexible connection between the two jaws 27.

In the modification shown in Fig. 9, the material used is flat sheet stock as distinguished from round wire and the loop 29 is formed by slitting the stock and separating the portions 30 and 31 to provide an opening 32 between them into which the rolled ends 33 of the upper bar 34 extends to cause the 10 same type of biting engagement with the fabric as heretofore described.

The foregoing description is directed solely towards the construction illustrated, but I desire it to be understood that I reserve the 15 privilege of resorting to all the mechanical changes to which the device is susceptible, the invention being defined and limited only by the terms of the appended claim.

I claim:

20 A collar holder comprising two sets of wire jaws disposed in opposite directions, each set having one jaw provided with an offset portion in the extent of the wire and folded back upon itself to meet said offset portion and 25 form an open loop with the opening in said loop extending in line with said jaw, and the other of said jaws located in the plane of the extent of said opening of said loop and extending thereinto.

30 In testimony whereof I affix my signature.
OSCAR CARLSON.
